ATTORNEY

UNITED STATES PATENT OFFICE

HARRY H. SCHROYER, OF CHICAGO, ILLINOIS, ASSIGNOR TO MORTON MANUFACTURING COMPANY, A CORPORATION OF ILLINOIS

RELEASEABLE CURTAIN-ROLLER MOUNTING

Application filed March 11, 1927. Serial No. 174,650.

This invention relates to an improved resilient mounting spring adapted to facilitate the removal or mounting of a curtain roller in a window frame.

It is an object of this invention to provide a bowed spring bracket for use on a window frame whereby a curtain roller may be easily mounted in place for use or removed by merely compressing the improved resilient bracket.

It is also an object of this invention to provide a bowed spring bracket adapted to carry a bearing socket permitting the gudgeon at one end of a curtain roller to be easily mounted in place in said bearing socket or removed therefrom when the spring bracket is compressed.

It is an important object of this invention to provide an improved releasable curtain roller and a pair of supporting sockets one of which is carried by a spring bracket which is adapted to be mounted on one of the window frame stiles, permitting the roller to be easily mounted in place or removed from engagement with its respective supporting sockets.

A further object is to provide a single piece spring metal bracket which will effectively retain a shade roller in position in a window frame and which will compensate for shade rollers of slightly different lengths.

Other and further important objects of this invention will be apparent from the disclosures in the specification and the accompanying drawings.

This invention (in a preferred form) is illustrated in the drawings and hereinafter more fully described.

On the drawings:

Figure 1 is a fragmentary elevational view of a curtain roller and an improved mounting spring embodying the principles of this invention, showing fragmentary portions of

window frame jambs between which the device is mounted.

Figure 2 is an elevational view of the spring bracket taken on line II—II of Figure 1.

Figure 3 is a longitudinal section of the spring bracket.

As shown on the drawings:

The reference numerals 1 and 2 indicate a pair of window frame side members or jambs between which a spring curtain roller 3 is adapted to be easily mounted or removed. Rigidly mounted by means of screws 4, or other suitable means, upon the inner face of the frame jamb 1 is a roller supporting socket or bearing 5 provided with a suitable recess or aperture for removably receiving a pin or gudgeon 6 axially projecting from one end of the roller 3. Projecting axially from the other end of the roller 3 is a second pin or gudgeon 7 which is adapted to be removably engaged in a roller supporting bearing or socket 8 having a recess or pocket 9 in which said gudgeon 7 is adapted to be journaled or seated. The bearing socket 8 is riveted or otherwise secured to the middle portion of the outer or convex face of a bowed plate spring bracket 10 the lower end of which terminates in a flat apertured shank 11. Retaining screws 12 project through the openings in the bracket shank 11 to hold said spring bracket mounted in place on the inner face of the frame jamb 2. The upper end of the bowed spring bracket 10 is curled to form a hook shaped contact head 13 which frictionally seats against the inner face of the frame jamb 2, as clearly illustrated in Figure 1.

From the description it will be noted that a simplified form of resilient mounting has been provided for a spring curtain roller, permitting the curtain roller to be easily mounted in place by first engaging the gudgeon 6 in the supporting socket 5 and then com-

pressing the bowed spring bracket 10 to permit the gudgeon 7 at the other end of the roller 3 to be engaged in the resiliently supported socket or bearing member 8 carried by the spring bracket 10. Upon release of the compressed spring bracket 10 said bracket will spring back into its bowed normal position holding the socket 8 in resilient engagement with the gudgeon 7, thereby supporting the roller 3 in an operative position ready for use. To remove the roller from its support it is only necessary to compress the spring bracket 10 to release the gudgeon 7, permitting the roller to be removed from its engagement with the socket 5.

While the improved resilient mounting spring or bracket 10 is shown secured in position upon the inner face of the frame jamb 2 it will, of course, be understood that the mounting bracket 10 may be conveniently seated within a slot within the jamb 2 allowing the socket 8 to project sufficiently to receive the roller gudgeon 7.

With the improved type of spring bracket 10 attention is called to the fact that rollers of different length may be rotatably mounted in the supporting bearings 5 and 8, since any variation in the length of rollers used will be taken up by the spring bracket 10.

30 The use of the bowed spring bracket 10 assures firm support of the shade roller in its brackets as the bracket 10 urges the roller 3 against the other bracket 5.

I am aware that many changes may be made, and numerous details of construction may be varied through a wide range without departing from the principles of this invention, and I therefore do not purpose limiting the patent granted hereon, otherwise than necessitated by the prior art.

I claim as my invention:

1. A curtain roller bracket mounting comprising a bowed plate spring, an apertured flat shank integrally formed on one end thereof to permit mounting of the bowed spring, a rolled head integrally formed on the other end of said bowed spring and adapted to have sliding engagement with the support on which the mounting is engaged, and a roller gudgeon receiving socket mounted on the convex face of said bowed plate spring.

2. A shade roller bracket formed from a single piece of spring metal having a flat lower attaching portion and a bowed upper portion, and a socket secured to said bowed portion, the end of the bowed portion remote from the attaching portion being rolled outwardly and free to move.

60 3. A shade roller mounting comprising a socket member for receiving one end of a shade roller, a bracket for the other end of said roller, said bracket comprising a flat spring member having an apertured lower attaching portion formed from a single piece of spring metal and a bowed upper portion

having a socket secured thereto for receiving the adjacent end of the shade roller, the end of the bowed portion remote from the attaching portion being curled outwardly and free to move, said bowed portion urging the shade roller against the socket at its other end.

In testimony whereof I have hereunto subscribed my name at Chicago, Cook County, Illinois.

HARRY H. SCHROYER.
